BOOKCASE

William B. Cobbs, Tuscaloosa, Ala.

Application August 8, 1949, Serial No. 109,167

1 Claim. (Cl. 211—42)

1

This invention relates to new and useful improvements in structural refinements in book cases, particularly multiple book case sections such as are used in libraries, etc; and the principal object of the invention is to facilitate convenient and expeditious cleaning of the book shelves.

In accordance with conventional practice it is necessary to remove books from the case in order that accumulation of dust may be removed from the shelves, and the instant invention seeks to eliminate this tedious cleaning procedure by the provision of what may be referred to as a replaceable shelf, the same being intended to be substituted for a book carrying shelf while the latter is removed for cleaning without the necessity of actually removing books from the case. Some of the advantages of the invention reside in its simplicity of construction, in its convenient and expeditious operation, and in its adaptability to economical manufacture.

With the above more important objects and features in view and such other objects and features as may become apparent as this specification proceeds, the invention consists essentially of the arrangement and construction of parts as illustrated in the accompanying drawings, in which:

Figure 1 is a front elevational view of the invention;

Figure 2 is a top plan view of one of the shelves used in the invention;

Figure 3 is a vertical cross sectional detail showing the initial step in the shelf-replacing operation;

Figure 4 is a fragmentary cross sectional detail, similar to that illustrated in Figure 3, but showing an ultimate step in the shelf-replacing operation;

Figure 5 is a fragmentary cross sectional detail of one of the latches used in the invention;

Figure 6 is a fragmentary elevational view, taken substantially in the plane of the line 6—6 in Figure 5;

Figure 7 is a cross sectional detail, taken substantially in the plane of the line 7—7 in Figure 2; and,

Figure 8 is a cross sectional view, similar to that shown in Figure 5, illustrating a modified embodiment of the latch.

Like characters of reference are employed to designate like parts in the specification and throughout the several views.

Referring now to the accompanying drawings in detail, the invention is embodied in a book

case designated generally by the reference character 10, the same consisting of a pair of spaced upstanding side walls 12 which are connected together in any suitable manner, such as for example, by a transverse top wall 14, and if desired, by a back wall 16, as will be clearly apparent.

A plurality of individually replaceable shelves designated generally by the reference character 18 are receivable in vertically spaced relation in the book case, and since the arrangement and mounting of these shelves is identical, it is believed that a description of one will suffice for all.

Each of the shelves 18 consists of a rectangular panel 20 provided with a perimetric frame 22 (see Figure 2), the panel 20 being formed with a set of longitudinally extending recesses or grooves 24 to accommodate a set of rollers 26 which are rotatably journaled in the end portions of the frame 22, as will be readily understood.

If desired, the end portions of the frame 22 may be provided with notches 28 (see Figure 7) to receive trunnions 30 with which the ends of the rollers 26 are equipped, whereby the rollers may be removed from the shelf for cleaning purposes.

In any event, it is to be noted that the rollers 26 project somewhat above the upper surface of the panel 20, so that when the invention is placed in use, books may be easily slid on the shelf and removed therefrom with equal expediency, this of course being facilitated by the rotatable rollers adapted to engage the lower edges of the books 32.

Each shelf 18 is supported in position in the book case by two pairs of supporting elements or latches 34, which are mounted in pairs on the opposing, inner surfaces of the side walls 12, as will be presently described.

The latches 34 are equipped with a transverse pin 36 which is rotatably and removably journaled in a pair of transversely spaced eyes 38 provided in a recess 40 with which the inner surfaces of the side walls 12 are formed, several of these recesses and eyes being provided as is shown in Figure 3, so that the latches 34 may be removed from one set of recesses and applied to another, in order to facilitate adjustment for varying vertical spacing and height of the several shelves.

The latches 34 have outer end portions provided with flat heads 42 which are adapted to supportably engage the underside of the shelves 18 when the latches are in a projected, substan-

tially horizontal position wherein they rest upon the lower edges 44 on the recesses 40, as illustrated by full lines in Figure 5.

However, it is to be noted that the latches 34 may be swung upwardly and inwardly into the recesses 40 as indicated at 46 in Figure 5, in which position the latches are almost fully retracted into the recesses. However, suitable stop lugs 48 are provided on the latches and are adapted to engage the inner end wall 50 of the recess 40 to prevent the latches from being retracted too far into the recess which, if permitted to occur, would not allow the latches to return to their projected, horizontal positions by influence of gravity.

It is to be noted that the shelves 18 are equipped with suitable handles 52, and when the invention is placed in use, the latches 34 are in their horizontal, projected positions and the shelves are supported by the latches, so that books indicated at 32 may be positioned on the shelves, as will be clearly apparent.

However, assuming that the shelves are to be cleaned to remove accumulated dust, etc., the initial step in the cleaning operation is to employ one of the shelves (which may be set aside for this sole purpose) and placed below the latches 34 of the shelf which is to be cleaned, as indicated in the lower portion of Figure 3. Thereupon, by exerting upward pressure on the lower shelf as indicated at 54, both shelves as well as the books on the upper shelf may be shifted upwardly, causing the latches to retract into their recesses until the lower shelf clears the latches, whereupon the latter are automatically returned to their projected positions by gravity and the two superimposed shelves, as well as the books on the upper shelf, are supported by the latches, as illustrated in Figure 4.

A transverse retaining bar 56, supported by suitable hooks 58, may extend between the side walls 12 substantially above the shelves, so as to retain the books in the book case while the upper shelf is withdrawn as illustrated at 60 in Figure 4, whereupon the books simply drop on the lower shelf and the withdrawn shelf may be subjected to cleaning without actually removing the books from the case. Needless to say, after the withdrawn shelf is cleaned, it may be substituted in the manner above described for another shelf when the cleaning operation is completed.

Finally, reference may be drawn to a modified embodiment of the invention illustrated in the accompanying Figure 8, wherein the pivotally mounted latches 34 are substituted by a spring pressed slidable bracket or latch 62 which is retractable against the resiliency of a spring 64 into a cup 66 mounted in the side wall 12, while a keeper pin 68, movable in a slot 70 in the latch 62, is used for preventing the bracket or latch

from sliding outwardly to an excess, as will be clearly apparent. The projecting end portions of the latches or brackets 62 are undercut in a manner to provide cams 63 with which the shelves 18 are engageable for retracting said latches or brackets.

It is believed that the advantages and use of the invention will be readily understood from the foregoing disclosure and accordingly, further description thereof at this point is deemed unnecessary.

While in the foregoing there has been shown and described the preferred embodiment of this invention it is to be understood that minor changes in the details of construction, combination and arrangement of parts may be resorted to without departing from the spirit and scope of the invention as claimed.

Having described the invention, what is claimed as new is:

In a book case, the combination of a pair of spaced upstanding side walls, retractable supports projecting inwardly from opposing surfaces of said walls, a removable book receiving shelf 25 positioned on said supports, a second shelf having a set of rotatable rollers thereon, said second shelf being receivable between said supports and the first shelf for supporting said first shelf on said supports whereby the underside of said first 30 shelf may engage said rollers, and a removable book retaining member extending transversely between said side walls above said shelves.
